COMBINED BINOCULAR AND RADIO SET

Victor Petrusk, 14611 Halsted St., Harvey, Ill. 60476

Filed Aug. 6, 1965, Ser. No. 86,482

Term of patent 14 years

(Cl. D56—4)

FIG. 1 is a rear, top and left side perspective view of a combined binocular and radio set, showing my new design;

FIG. 2 is a left side elevational view, the right side being substantially a mirror image thereof;

FIG. 3 is a front elevational view; and

FIG. 4 is a top plan view thereof.

The bottom is plain and unornamented. Portions of the drawing figures are diagonally lined to indicate transparency.

I claim:

The ornamental design for a combined binocular and radio set, as shown and described.
